CLAIM

The ornamental design for a motor grader rear section housing, as shown and described.

DESCRIPTION

FIG. 1 is a perspective view of a motor grader rear section housing showing our new design;

FIG. 2 is a right-side elevational view of the motor grader rear section housing;

FIG. 3 is a left-side elevational view of the motor grader rear section housing;

FIG. 4 is a rear elevational view of the motor grader rear section housing;

FIG. 5 is a front elevational view of the motor grader rear section housing; and,

FIG. 6 is a top plan view of the motor grader rear section housing.

The broken lines shown represent unclaimed subject matter and form no part of the claimed design.
